CARRIER HANDLE FOR GARMENT HANGERS

James A. Belland, 310 Wildwood Road, Willernie, Minn. 53090; and Eugene Brown, 2600 Mayfair Ave.; and David De Wuske, 103 Wildwood Road, both of White Bear Lake, Minn. 53090

Filed Dec. 14, 1970, Ser. No. 26,446

Term of patent 14 years

Int. Cl. D8—05

U.S. Cl. D8—154

FIG. 1

FIG. 2

FIG. 3

FIG. 4

FIG. 5

FIG. 1 is a top plan view of a carrier handle for garment hangers showing our new design;

FIG. 2 is a view from one end thereof;

FIG. 3 is a side elevation thereof;

FIG. 4 is a view from the other end thereof; and,

FIG. 5 is a bottom plan view thereof.

We claim:

The ornamental design for a carrier handle for garment hangers, substantially as shown.
